UNITED STATES PATENT OFFICE.

HAROLD JAMES PAYN, OF WEYBRIDGE, ENGLAND, ASSIGNOR TO VICKERS LIMITED,
OF WESTMINSTER, ENGLAND, A BRITISH COMPANY.

AUTOMATIC GUN CARRIED BY AIRCRAFT.

Application filed January 23, 1928, Serial No. 248,900, and in Great Britain January 19, 1927.

This invention relates to automatic guns carried by aircraft in positions some distance removed from, and out of ready reach of, the gunner, for example in or on the wings in 5 the case of an aeroplane. It is desirable to provide such guns with a cocking and loading lever under the control of the gunner for reproducing manually the movements of the barrel and the gun mechanism which occur 10 during firing so as to load the gun initially and, in the case of a misfire, to eject the defective cartridge and cock and reload the gun.

In guns situated as described above, we, 15 according to this invention, provide in conjunction with each gun an operating handle within reach of the gunner and a connection between this handle and the cocking and loading lever on the gun. In the case of a gun 20 mounted in or on one of the wings of an aeroplane, this connection may be in the form of a transverse shaft one end of which is connected to the said handle (arranged in or close to the cock-pit) and the other end operates upon the cocking and loading lever 25 of the gun. Alternatively a system of levers and links may be used.

In order that the said invention may be clearly understood and readily carried into effect, the same will now be described more fully with reference to the accompanying drawings, in which:—

Figure 1 is a diagrammatic perspective view showing an automatic gun which is 35 mounted on the wing of an aeroplane and has its cocking and loading lever operated from a distance by mechanism including a transverse shaft, and

Figure 2 is a view similar to Figure 1 showing a system of levers and links replacing the transverse shaft.

In both of the figures A is the mechanism casing of an automatic gun mounted on an aeroplane wing which is shown by chain lines 45 at A¹, the framework of the fuselage being represented by chain lines at A² and the cock-pit at A³. B represents the cocking and loading lever for co-operating with the crank handle A⁴ of the gun as aforesaid. This lever 50 which is pivoted at B¹ to the mechanism casing A, is shown as being of the "Hyland" type described in the specification of British

Patent No. 126,670. In the examples shown this lever B is associated with an auxiliary lever C as is described in the specification of 55 our patent application filed concurrently herewith, this auxiliary lever being for the purpose of co-operating with the crank handle A⁴ in order to force the lock of the gun into its forward position in the event of the 60 normal forward movement of the lock being stopped by the jamming of an oversize cartridge in the cartridge chamber of the barrel. In both the constructions shown the auxiliary lever C is in the position it occupies when it has been operated as stated 65 above.

In the construction according to Figure 1, D is a rotary shaft the inner end of which has a handle D¹ arranged in or close to the 70 cock-pit A³ so that it can be operated by the gunner, and the outer end of this shaft carries a crank D² connected by a pin D³ to part of the auxiliary lever C, the said pin D³ being arranged to pass clear of the mechanism casing during the actuation of the said 75 shaft. Angular displacement of the shaft D in an anti-clockwise direction when viewed from its outer end displaces the levers B and C together (owing to the co-operation of a 80 stop on the lever C with the lever B) so as to cause the lever B to co-operate with the crank handle A⁴, whilst angular movement of the said shaft in the reverse direction causes the lever C alone to move and co-operate with the said crank handle, this lever being returned to its original position by a spring C¹ when the handle D¹ is released. In the case 85 of an aeroplane in which the whole or a part of each wing is made removable the shaft D 90 would be made in two parts with a clutch between them to permit separation to occur when the wing or wing part is removed.

In the construction according to Figure 2 the handle D¹ is connected by a link D⁴ to a 95 bell-crank lever D⁵ which is connected by a link D⁶ to a second bell-crank lever D⁷ connected by a link D⁸ to the aforesaid auxiliary lever C, the operations being similar to those described with reference to Figure 1. It will 100 be understood that the plane of rotation of the levers D⁵ and D⁷ is at right angles to that of D¹ and B.

In cases in which only the cocking and

loading lever B is employed the pin D³ of Figure 1 and the link D⁸ of Figure 2 would be connected to part of the said lever B.

What I claim and desire to secure by Letters Patent of the United States is:—

1. In an automatic gun, a cocking and loading lever for reproducing manually movements of the gun mechanism that occur during operation of the gun, an operating handle remotely located with respect to the gun, and a rigid connection between said handle and the cocking and loading lever.
2. In an automatic gun, a cocking and loading lever for reproducing manually movements of the gun mechanism that occur

during operation of the gun, an operating handle remotely located with respect to the gun and a transverse shaft connecting said handle and the cocking and loading lever.

3. In an automatic gun, a cocking and loading lever for reproducing manually movements of the gun mechanism that occur during operation of the gun, an auxiliary lever cooperating with the crank handle of the gun to force an over-size cartridge into the cartridge chamber of the gun barrel, and remotely located means for actuating said auxiliary lever.

HAROLD JAMES PAYN.
